UNITED STATES PATENT OFFICE.

EDWIN L. MILLER, OF KANSAS CITY, MISSOURI.

GAS-GENERATING OIL-BURNER.

1,387,506.

Specification of Letters Patent. Patented Aug. 16, 1921.

Application filed October 11, 1919. Serial No. 330,092.

To all whom it may concern:

Be it known that I, EDWIN L. MILLER, a citizen of the United States, residing at Kansas City, in the county of Jackson and State 5 of Missouri, have invented a new and useful Gas-Generating Oil-Burner, of which the following is a specification.

My invention relates to gas generating oil burners and particularly to a device of this 10 character patented to me on June 17, 1919, No. 1,307,206.

The object of the invention is to improve the gas generating oil burner by the provision of a steam generator whereby steam 15 vapor shall mix with the gas generated and the combined elements mixed with air, to produce a substantially perfect combustible mixture which shall burn and radiate great heat.

I attain this object and other advantages by means of the construction and combination of parts illustrated in the accompanying drawing in which—Figure 1, is a vertical section through the device embodying my 20 invention. Fig. 2, is the same, and showing a gas retort assembled with the device. Fig. 3, is a top plan view of the device shown in Fig. 1. Fig. 4, is an end view of the nozzle for venting the combustible mixture 25 and, Fig. 5, is an end view of the nozzle for venting steam vapor.

The device comprises a horizontally disposed plate 1, having a vertical flange on its upper side, at its peripheral edge. An 35 annular vertical flange 3, is formed centrally on the upper side of the plate 1, and forms with the plate a basin 4. Annular vertical flanges 5, are formed at opposite sides of the plate, in which the legs of a substantially U-shaped tube 6, are placed and openings 30, in the base 1, allows fresh air to enter the tube. A tubular projection 7, is formed integral with the lower side of the arch of the tube 6, and communicates with the latter. An opening 8, is provided in the upper side of the tube 6, and is adapted for receiving the tubular stem 9, of a retort 40 or a steam pipe 11, as shown in Fig. 1. A mixing chamber 12, consisting of a cross shaped coupling, is arranged to be stationed in the arch of the tube 6, and its upper end is adapted for receiving the end of a steam pipe, in this instance pipe 11, which conducts steam from a hollow steam generating ring 50 14, to the mixer 12. A nozzle 15, having a diminutive orifice 16, is connected with the

end of the steam pipe 11, within the mixing chamber. A water supply pipe 17, is connected between the steam generating ring 14, and a source of water supply, not shown. 60 An oil pipe 18, is arranged to pass through the one leg of the tube 6, and is connected with the side of the mixing chamber and with a fuel supply, not shown. A nozzle 19, having an orifice 20, which is a little 65 larger than the orifice in the nozzle 15, is connected with the lower end of the mixer and arranged to vent combustible mixtures downwardly in the projection 7, of the tube 6. In the case of the device with the retort 70 10, the stem 9, thereof functions the same as the mixing chamber 12, to mix gas and steam, the air mixing with the product as before.

To operate the device a quantity of oil is 75 permitted to flow from the pipe 18, into the mixer 12, and to gravitate therefrom through the nozzles 15 and 19, to the basin 4, where the oil is ignited and allowed to burn. The flame thus produced effects a rapid heating 80 of all the parts of the device and, eventually, the oil will be volatilized in the upper portion of the pipe 18, and the gas, escape therefrom through the mixer and the nozzles 15 and 19. When gas is generated, the 85 water in the pipe 17, is permitted to flow into the steam generating ring 14, in any suitable quantity, and the water striking the hot inner surface of the ring, is immediately converted into steam, in the well 90 known manner. The steam thus generated flows through the pipe 11, and through the nozzles 15 and 19, mixing in the latter with the gas from pipe 18, the mixture thus produced being discharged from the nozzle 19, 95 into the extension 7, of the tube 6, where it is further mixed with air flowing therethrough from the tube 6. The ultimate mixture of gas, steam, and air, in proportions limited by the discharge orifices of the nozzles 15 and 19, and the capacity of the extension 7, of the tube 6, forms a combustible gas which will burn with intense heat. The compactness of the device adapts it for use in heating furnaces and stoves, in which the 100 device may be placed on the usual grate bars.

The retort 10, shown in Fig. 2, is a provision for more rapid generation of gas, by introducing additional heated surface to receive the oil, and thereby obtaining greater 110 quantity of gas.

Having described my invention what I claim is—

In a gas generating oil burner, the combination of a base plate, an inverted U-shaped air duct mounted vertically on said plate, the arch in said pipe being provided centrally on its lower side with a tubular discharge opening, a mixing chamber arranged in the arch of said duct, a steam generator connected with said mixing chamber and adapted for venting therein a diminutive jet of steam, a pipe arranged in said air

duct and adapted for the delivery of oil and gas therefrom to said mixing chamber, and a nozzle connected with said mixing chamber and adapted for venting the contents of the chamber into the discharge opening of said air duct. 15
